UNITED STATES PATENT OFFICE.

JOHN L. TANDY, OF KANSAS CITY, MISSOURI.

BED-SPRING COVER.

1,227,693.

Specification of Letters Patent. Patented May 29, 1917.

Application filed January 21, 1915. Serial No. 3,552.

To all whom it may concern:

Be it known that I, JOHN L. TANDY, a citizen of the United States, residing at Kansas City, in the county of Jackson and 5 State of Missouri, have invented certain new and useful Improvements in Bed-Spring Covers, of which the following is a specification.

This invention relates to bedding and my 10 object is to produce a new article of bedding for interposition between the bed spring and the mattress and bed covering for protecting the mattress and covering from contact with the bed spring.

15 A further object is to produce an article of bedding which will prevent lateral shifting movement of the mattress or bulging of the same and give the bed when made up the finished appearance or effect of a bed 20 equipped with a box mattress.

Another object is to produce a protector underlying the mattress which will accommodate the sagging of the bed spring under the weight of the occupant or occupants 25 thereof, without the possibility of being torn or injured.

With these general objects in view the invention consists in certain novel and peculiar features of construction and organization 30 as hereinafter described and claimed; and in order that it may be fully understood reference is to be had to the accompanying drawing, in which—

Figure 1, is a perspective view showing 35 a bed spring equipped with a cover or protector embodying my invention, the cover being broken away to disclose features otherwise hidden, and the mattress being indicated by dotted lines.

40 Fig. 2, is a top view of a bed spring equipped with side rails for holding the bed spring cover elevated adjacent the side margins of the spring in a manner indicated in Fig. 1.

45 Fig. 3, is a side view of a bracket shown by Fig. 2.

Fig. 4, is an enlarged cross section taken on the line IV—IV of Fig. 3, with the protecting cover in place.

50 Fig. 5, is a similar view with certain parts occupying a different position of adjustment from that shown in Fig. 4, and with the bed spring fabric resting upon spiral springs.

55 Fig. 6, is a fragmentary perspective view indicating a bed spring fabric equipped

with a modified form of side rail and support therefor.

In the said drawing, 1 indicates one of the customary pair of side rails and 2—2 a pair 60 of the customary sets of end brackets and 3—3 the end bars adapted to connect opposite brackets 2, these parts constituting a common and well known form of frame for the support of any suitable bed spring fabric 65 4. The bed spring fabric shown is connected by helicals 5 to the end bars 3 and is equipped at each side margin as usual with a flat marginal bar 6.

In Fig. 5, the fabric is shown as adapted 70 for support by underlying spiral springs 7, the fabric customarily used with springs 7 being provided with cylindrical bars or rods 8.

The fabric is equipped at or near its side 75 margins with what may be termed rails 9 which rails will be of such character that they will bend to accommodate bending movement of the fabric and return to normal condition when the fabric returns to normal condition. If the rails are in the form of wire 80 rods they will preferably be formed with rounded ends or loops 10 so as to avoid the possibility of tearing any part of the bedding or of injury to the hand of the person 85 who may make up the bed. Preferably the rails will be composed of sections 11. In Figs. 2 and 3 said sections 11 will be pivotally linked together as at 12 about midway 90 the length of the bed and the linking portion will preferably be the upper end of an upwardly projecting arm of a right angle-shaped bracket 13 resting upon the fabric. 95

Substantially similar brackets 14 will rest upon the fabric near the ends of the same 100 and will preferably be formed with eyes 15 at their upper ends through which the sections 11 will slidably extend. In Figs. 2 to 4 inclusive a clamp bar 16 is arranged under the horizontal arms of the brackets 13 and 14 and at the opposite or underside of the spring fabric, bolts 17 and nuts 18 extend through the said superposed parts to clamp them firmly to the fabric as shown most clearly in Fig. 4, in which figure and 105 Fig. 3, it will be noticed that the marginal strips or bars 6 fit flatly between the bracket and the bar.

In order to accommodate the rail supporting devices for use upon bed spring 110 fabrics of the type shown in Fig. 5, the outer ends of the bar 16 are provided with under-

lying inturned hooks 19, for the reception of the rod 8 as indicated in Fig. 5. The inner end of the horizontal arm of each bracket 13 and 14 is provided with an upwardly bowed portion 20 to facilitate the slippage thereover of a cover hereinafter mentioned, and also to guard against the latter catching on the inner ends of said arms of the brackets, and to protect said cover from the inner ends of the bars 16 in the event that the cover sags through interstices of the bed spring fabric as will occur where the interstices are large and the bed is occupied, the inner ends of said bars 15 are preferably upturned slightly as at 21 under the arched ends 20 of the overlying brackets.

In the event that the mattress is somewhat narrower than the bed spring fabric provision is made for adjusting the rail support or brackets inwardly upon the bars 16 as indicated in Fig. 5, this adjustment being accomplished by inserting the bolt 17 through different holes in the arms of the brackets or through both the arms of the brackets and bars 16.

In Fig. 6, I show brackets made of wire as a substitute for the rod supports described. Each of the wire brackets can be 30 made from a single piece of wire bent to form a hook 22 to underlie a flat strip 6 of the bed fabric and spring arms 23 to overlie said strip and the bed fabric and be hooked at their free ends to the latter. In 35 intermediate the hook 22 and hook arms 23, the wire is bent to form standards composed of upright portions 24 extending upward from the outer ends of the hook arms 23, upright portions 25 extending upward from 40 the outer end of the hook 22 and eyes 26 uniting the arms 24 and 25, and to accommodate this bracket to a side rod such as shown at 8, (Fig. 5) the hook 22 can be formed with a depending loop 27.

45 The linking portion between a supporting bracket of the type shown in Fig. 6 and the sections 11 of the side rails 9 may be in the form of a rod 28 pivotally connected at its ends to the inner ends of the sections 11, and to make provision for fastening the 50 cover to said brackets, the upright arms of brackets 13 and 14 and upright portions 25 of the wire bracket will be provided with holes 29.

55 To protect the mattress from the bed springs, I provide a cover which is placed upon the bed spring, and adjacent the side margins of the latter, is looped over the rails 9 and draped at the outer sides of the bed 60 spring, the cover preferably being of sufficient length to also drape over the end bars 3 of the spring frame so that it will completely hide the latter from view before the 65 mattress and the bed covers are placed upon the bed.

The bed spring cover is adapted for lateral expansion between its side walls or raised portions to accommodate an increase in the distance between said walls due to the sagging of the spring fabric under the imposition of weight upon the bed and to accommodate lengthwise expansion of the cover, it will be so draped as to have some fullness at its ends where it extends over the end bars 3 of the bed frame.

75 In the preferred construction, I secure expansibility of the cover by making the same of two sections 30 which overlap at their inner edges. The ends of the cover which are draped over the end bars of the bed 80 frame are identified by the characters 31 and the draped side portions are identified by the characters, 32, the upwardly projecting side portions, produced by looping the sections of the cover over the side rails are 85 identified by the characters 33.

The sections of the cover where they extend upwardly against the inner sides of the upwardly projecting arms of the brackets which support the side rails, are 90 secured in fixed relation to said rail supports by rivets 34 or equivalent fastening devices, as shown clearly in Figs. 1 and 4.

95 At the ends where the cover sections extend over the end bars 3, is indicated a fullness 35 and to hold the cover against creepage endwise bodily, each section 30 is provided with a tape as at 36 adapted to be drawn taut and tied together as shown in Fig. 1.

100 For the purpose of keeping the cover taut transversely without interfering with its expansion in one direction the inner margin of each section is connected by elastic strips 37 to the adjacent section. In the sagging 105 of the spring under the imposition of weight thereon, by a person lying upon the mattress, the elastic strips will stretch and when the weight is removed they will retract provided they are sufficiently strong to overcome the resistance offered by the mattress 110 resting on the cover.

115 By reference to Fig. 1, it will be seen that the mattress 38, indicated by dotted lines, rests upon the cover between and projects 120 a distance above the side walls of the cover in excess of the depth which it is possible for it to sag, hence to a person lying or sitting upon the mattress, the presence of the rails 9 and brackets 13 and 14, or the wire 125 brackets shown by Fig. 6, will not be noticeable, although said side rails and brackets in coöperation with the walls of the cover will prevent the mattress working bodily sidewise on the cover or from bulging outward beyond the sides of the spring bed.

130 A bed equipped with this cover provided with side walls produced as explained or by an equivalent construction, will give the bed when made up a finished appearance.

From the foregoing it will be seen that a cover of the character shown and described will not only protect the mattress and guard against tearing of the sheets and other bedding thereon, by contact with the end bars 5 but will also largely prevent the accumulation of dust upon the upper side of the spring bed fabric as well as on the end bars of the bed frame.

10 I claim:

1. The combination with a bed spring of a series of brackets secured to the side portions of the spring, and rail sections above the spring and pivotally linked together at 15 their inner ends and supported by one of said brackets and slidably carried at their outer ends by the remaining brackets.

2. The combination with a rectangular frame, a mattress fabric stretched over said 20 frame and secured at its ends to the ends of said frame, central devices attached to the side margins of said mattress fabric and projecting upwardly therefrom, devices attached to the side margins of the mattress 25 fabric at opposite sides of said central devices and projecting upwardly like the latter, rails substantially paralleling and disposed above the side margins of the mattress fabric and secured at their inner ends 30 to the upwardly projecting portions of said central devices and fitting slidably in the said devices disposed at opposite sides of said central devices, and a cover spread upon the mattress fabric and looped over and 35 draped downwardly at the outer sides of said rails and the sides of said frame and also draped over the ends of said frame.

3. The combination with a rectangular frame, a mattress fabric stretched over said 40 frame and secured at its ends to the ends of said frame, central devices attached to the side margins of said mattress fabric and projecting upwardly therefrom, devices attached to the side margins of the mattress 45 fabric at opposite sides of said central devices and projecting upwardly like the latter, rails substantially paralleling and disposed above the side margins of the mattress fabric and secured at their inner ends 50 to the upwardly projecting portions of said central devices and fitting slidably in the said devices disposed at opposite sides of said central devices, a cover spread upon the mattress fabric and looped over and draped

downwardly at the outer sides of said rails 55 and the sides of said frame and also draped over the ends of said frame, and means attached to the draped portions of said cover to secure the draped end portions of the cover against the ends of said frame. 60

4. The combination with a rectangular frame and a bed spring secured at its ends to the ends of said frame, of elevated side rails for said bed spring, and a cover resting upon the latter and composed of two longitudinally-extending sections overlapping at 65 their inner margins and at their outer margins looped over the said rails, and elastic connections between said sections to hold them in overlapped relation. 70

5. The combination with a bed spring of rails above the side portion of the springs, means for supporting said rails at different points along the length of the bed spring and for maintaining the rails substantially 75 parallel with the said side portions of the bed spring regardless of whether the latter is straight or bent, means for securing the side rails different distances apart to accommodate mattresses of different width, 80 and a cover resting on the bed spring and looped over and secured in fixed relation to said rails and consisting of two sections which are overlapped at their inner edges. 85

6. The combination with a bed spring of rails above the side portions of the springs, means for supporting said rails at different points along the length of the bed spring and for maintaining the rails substantially parallel with the said side portions of the 90 bed spring regardless of whether the latter is straight or bent, means for securing the side rails different distances apart to accommodate mattresses of different width, a cover resting on the bed spring and looped over 95 and secured in fixed relation to said rails, and consisting of two sections which are overlapped at their inner edges, and elastic means tending to hold the inner edges of the sections of the cover in overlapped relation. 100

In testimony whereof, I affix my signature, in the presence of two witnesses.

JOHN L. TANDY.
